FIG. 4.

Inventor

H. R. Van Deventer,

UNITED STATES PATENT OFFICE.

HARRY RANDOLPH VAN DEVENTER, OF SUMTER, SOUTH CAROLINA, ASSIGNOR TO
SPLITDÖRF ELECTRICAL COMPANY, OF NEWARK, NEW JERSEY, A CORPORATION
OF NEW JERSEY.

IGNITION DEVICE.

1,257,155.

Specification of Letters Patent. Patented Feb. 19, 1918.

Application filed February 15, 1916. Serial No. 78,485.

To all whom it may concern:

Be it known that I, HARRY R. VAN DEVENTER, a citizen of the United States, residing at Sumter, in the county of Sumter and State 5 of South Carolina, have invented certain new and useful Improvements in Ignition Devices, of which the following is a specification, reference being had to the accompanying drawing.

10 This invention relates to ignition mechanism for internal combustion engines and has for its object the arrangement and combination in one compact unit of the magneto, the spark plug and the means for operating the magneto, thereby reducing to a minimum the mechanical and electrical connections necessary between these parts, and enabling all of the ignition equipment to be assembled at one point on the engine.

20 Specifically the invention relates to a high tension ignition system, in which a spark plug with fixed points or electrodes are used. It is customary in such systems to use a high tension oscillating magneto, and heretofore said magnetos have been equipped with end plates supporting a spring or springs connected to an arm on the magneto shaft, said arm being tripped by a suitable push rod or its equivalent in time with the 30 engine cycle, thereby generating a current, which is led to the plug, the timing of the ignition being effected by varying of time at which the magneto shaft is oscillated. Such arrangements are already well known.

35 My improvement consists of mounting the springs for oscillating the magneto directly on the adjacent support, eliminating a heavy frame work for the magneto, and the bearings of same from strain due to the tension 40 of the springs.

I consider that the actuating springs for the magneto are part of the engine mechanism and therefore I have separated these actuating springs from the magneto, permitting a magneto of standard construction to be used, and one which may be readily removed and replaced on the support provided without requiring careful and expert adjustment.

50 I also provide in case of emergency a battery interrupter mounted on the support and actuated by the mechanism provided for moving the generator, so that in case the generator is removed from the support a 55 battery coil may be connected to the spark

plug and interrupter and the running of the engine continued without interruption.

Figure 1 is a side view of an apparatus embodying my invention; Fig. 2 a front view of the support showing the interrupter 60 and the actuating means; Fig. 3 a side view of the complete apparatus showing more in detail the trip lever; and Fig. 4 a diagram showing the electrical connections. Like figures of reference denote the same parts 65 wherever they are shown.

1 denotes a support adapted to be secured to the side or end of the engine cylinder and provided with suitable bolt holes 2. 3 denotes the inner end of a spark plug adapted 70 to extend into the engine cylinder. The shell of 3 forms one electrode on the spark plug, and 4 the other.

Suitably journaled in the support 1 is the trip lever 5, the nose 6 of which is engaged 75 by the push rod 7, the latter being operated by the engine. For restoring 5 to its normal position shown in the figures springs 8 and 9 are provided. These springs and the trip lever 5 constitute an actuating mechanism for the high tension magneto 10, which is connected, by means of the bifurcated member 11, to the trip lever 5; and it will be seen that when the push rod 7 is forced upward, it rides past the end 6 of the trip 85 lever and releases the same, and that springs 8 and 9 cause the trip lever to violently oscillate, which oscillation is transmitted to the member 11, thereby operating the magneto to produce a spark. 90

It will be seen by removing the bolts 12 holding the magneto to the shelf 11 of the support 1, that the magneto may be removed from the support without in any way affecting the operation of the trip lever 5 and 95 its associated springs.

A suitable cable 13 serves to connect the high tension terminal on the magneto with the terminal of the electrode 4 in the spark plug, the return circuit being through the 100 framework.

If for any reason the magneto is removed from its support it is obvious that the source of current supply for the spark plug is disassociated therefrom, and to provide for 105 such occasions a suitable interrupter operating in unison with the operation of the trip lever 5 and thereby suitably timed to the engine is mounted on the support 1. This interrupter is shown in Fig. 2 and con- 110

sists of the arm 14 normally held in position against the trip lever 5 by means of the spring 15. This arm carries a contact point 6 normally in contact with a suitable point in spring 17. It will be obvious that the contact between 16 and 17 is interrupted each time the trip lever 5 operates.

- If it is desirable to use the outfit shown at Fig. 2 with battery as a source of current, 10 the magneto being omitted, the arrangement shown in Fig. 4 is employed. The magneto cable 13 is disconnected from the spark plug terminal 4 and the cable 18 from the induction coil is connected in place of 13. The 15 battery 20 is in series with the primary of the induction coil 19 and with the interrupter contacts 16 and 17, the latter being operated by the trip lever 5. As such arrangements are well understood, a detailed 20 description is not herein given, but it will be noted that the outfit shown at Fig. 2 is complete with everything necessary to furnish ignition for the engine, except the induction coil and battery.
25. To provide for any slight adjustment in timing I provide the set screw 21, which may be so adjusted as to vary the time of operation of the interrupter contacts 16 and 17 by varying the time at which trip lever 30 5 strikes arm 14.

I claim:

1. The combination with a support adapted to be secured to an engine, of a spark plug mounted on said support and having 35 fixed electrodes, a generator on said support electrically connected to said plug, and mechanism including a spring-actuated tripping device adapted to actuate said generator.
40. 2. The combination with a support adapted to be secured to an engine, of a spark plug mounted on said support and having fixed electrodes, a generator on said support

electrically connected to said plug, and mechanism including a spring-actuated tripping device adapted to actuate said generator, said mechanism including the spring-actuated tripping device being mounted wholly on said support.

3. The combination with a support adapted to be secured to an engine, of a spark plug mounted on said support and having fixed electrodes, a generator on said support electrically connected to said plug, and mechanism including a spring-actuated 55 tripping device adapted to actuate said generator, said generator being removable from said support without affecting the operation of the tripping device.

4. The combination, with a support adapted to be secured to an engine, of a spark plug having fixed electrodes, a generator electrically connected to said plug, mechanism including a trip device adapted to 60 actuate said generator, and a circuit interrupter operated by said mechanism, substantially as described.

5. The combination, with a support adapted to be secured to an engine, of a spark plug having fixed electrodes, a generator 70 electrically connected to said plug, mechanism including a trip device adapted to actuate said generator, and a circuit interrupter mounted on said support and operated by said mechanism, substantially as 75 described.

6. The combination, with a support adapted to be secured to an engine and forming an igniter flange, of a fixed spark gap carried thereby and projecting into the engine 80 cylinder, a circuit interrupter carried on said support, and means carried by said support for actuating said interrupter.

In testimony whereof I hereunto affix my signature.

HARRY RANDOLPH VAN DEVENTER.
